UNITED STATES PATENT OFFICE.

HARALD J. VENNES, OF NEW YORK, N. Y., ASSIGNOR TO WESTERN ELECTRIC COMPANY, INCORPORATED, OF NEW YORK, N. Y., A CORPORATION OF NEW YORK.

CARRIER-CURRENT SYSTEM.

Application filed December 21, 1920. Serial No. 432,316.

To all whom it may concern:

Be it known that I, HARALD J. VENNES, a citizen of the United States, residing at New York, in the county of Bronx, State 5 of New York, have invented certain new and useful Improvements in Carrier-Current Systems, of which the following is a full, clear, concise, and exact description.

This invention relates to carrier current systems and more particularly to means for improving the quality of the signal supplied to a transmitting circuit.

It is a well-known fact that the frequency supplied by a vacuum tube oscillator, such 15 as is used in carrier current systems, is to a considerable degree dependent on the impedance of the load circuit connected to the oscillator.

It is also a fact that when an alternating 20 voltage, impressed on the input circuit of a vacuum tube device, has an amplitude sufficient to make the grid positive with respect to the filament, a grid current will flow and hence lower the input impedance 25 of the device. Hence, when in a carrier telegraph system the output of an oscillator feeds into the input of an amplifier, it is obvious that the impedance of these circuits when connected together will depend upon 30 the amplitude of the oscillations to be impressed on the amplifier. This amplitude may be determined by using a potentiometer to interconnect the amplifier and oscillator but when the potentiometer setting is 35 changed the output impedance will be changed and as a result the frequency of the oscillations will be caused to vary.

Again, in such systems when signals are 40 being transmitted, the sending relay connects a low impedance path across the output circuit of the oscillator with the result that a surge will occur at the beginning and end of each signal. This seems to be caused by a sudden change of frequency at these 45 points in the signal periods: hence, sharp signal effects are impossible.

The primary object of this invention is to provide means whereby sharp signal effects may be obtained.

Another object of this invention is to provide means which will stabilize the frequency of the oscillations produced by an oscillator.

A further object is to provide an arrangement in which the impedance of the circuit

external to the oscillator circuits will be maintained substantially constant.

These objects and others which will appear as the nature of the invention is disclosed, may be accomplished by inserting a 60 large resistance in the circuit external to the oscillator, so that the impedance changes in said circuit due to the adjustment of the potentiometer or transmission of signals will not introduce material changes in the impedance of the output circuit of the oscillator. In this manner, the tendency of impedance changes in the external circuit to react upon the oscillator and change the frequency of the oscillations produced thereby 65 is avoided.

Different circuit arrangements embodying the invention are shown in the two figures of the attached drawings, wherein Fig. 1 shows an arrangement in which the oscillator is connected to the amplifier through a potentiometer and Fig. 2 shows an arrangement in which the oscillator is directly 70 connected to the amplifier.

Referring to Fig. 1 an oscillator of the 80 type described by R. V. L. Hartley in his patent for oscillation generators, No. 1,356,763, issued October 26, 1920, is illustrated. This oscillator comprises a space discharge device 1 having its grid or control electrode and its anode connected to the opposite terminals of an inductance 3, and its cathode connected to an intermediate point thereon. In shunt to this inductance is a variable condenser 4 which cooperates 85 with inductance 3 to constitute a tuned circuit adapted to determine the frequency of the oscillations generated. By varying the inductance 3, condenser 4, or both, the frequency of the oscillations may be varied. 90

Sources 5 and 6 respectively supply heating current to the filament of the vacuum tube devices employed in this system and plate current to the oscillator tube. The amount of current supplied by these batteries may be controlled by adjustable resistances respectively associated with them. These resistances should have sufficient inductance to prevent short-circuiting of the oscillations through the sources 5 and 6. 95

Condensers 7 and 8, designed to impose an infinite impedance to the flow of direct current but to permit alternating current to pass without appreciable attenuation, are inserted in the alternating current paths of 100 105 110

the oscillator circuits which connect the filament heating source 5 to the midpoint of the inductance 3 and the plate source 6 to one terminal of this inductance. In this manner, a conductive path for the current from the battery 5 to the grid element of the tube through the resistance 9 is determined and a path for the oscillatory current fed back is provided, but direct current from the source 6 is prevented from flowing to the tuned circuit and therethrough to the grid.

The potential generated by the oscillator is impressed across resistance 9 and the intensity of the electromotive force supplied to the grid circuit of the amplifier 10 may be regulated by adjusting the contact 11 associated with the resistance 9. Included in the circuit connecting the adjustable contact 11 and the grid of the amplifier 10 is a resistance 12, which will be referred to later, and associated with said circuit between the resistance 12 and the grid is a path 13 adapted to be grounded to effect signal transmission. A condenser is inserted in this path to prevent the flow of direct current from the grounded sources therethrough, while permitting the flow of oscillations when this circuit is completed.

30 A key has been herein shown to control the ground path. Any other means, for example, a line relay controlled by a distant or local operator, may be used for this purpose.

35 When no signals are being transmitted, the oscillations impressed upon the grid circuit of the amplifier will cause current variations of the same frequency in the plate current of the amplifier. This variable current is supplied to the tuned circuit constituted by the adjustable condenser 15 and the primary winding of the transformer 16, the secondary of which may be connected either to a transmission line or the antenna 40 of a radio system, whereby oscillations of definite frequency will be transmitted to the distant receiving station.

When it is desired to transmit a message to a remote station, the ground path 13 is closed and opened in accordance with any desired code to shunt the oscillations from the amplifier input circuit, thus suppressing the flow of variable current in its output circuit and hence the transmission of energy 50 to the distant station.

55 Plate current is supplied to the output circuit of the amplifier 10 by a source 17 through a retard coil 18, which serves to prevent the flow of the oscillations through the source 17, while permitting the flow of direct current from the source through the plate circuit of the amplifier.

60 A blocking condenser 19 is inserted between the plate source and the tuned circuit to prevent direct current supplied by

the source 17 from reaching tuned circuit 15-16, though offering substantially no impedance to the flow of alternating current circuit 15-16.

Resistance 12 bears such relation to the 70 impedance of the oscillator output circuit that variations in this impedance, resulting from changes in the setting of the potentiometer constituted by the resistance 9 and contact 11 or closing of the ground path 13 75 when signaling, will not be appreciable. In other words the resistance 12 should be so proportioned (in one case a resistance of 48,000 ohms gave satisfactory results), that the amplitude of the oscillations impressed across the input circuit of the amplifier will not be materially changed under the changing conditions stated above.

80 Referring to Fig. 2 the invention is shown applied to a system employing metallic or ungrounded circuits. In this figure the oscillator is of the same type as that shown in Fig. 1, but is directly connected to the amplifier 10 through the resistance 12. The signal path 13 is connected across the input circuit of the amplifier at a point between resistance 12 and the grid, and the potentiometer 9-11 is placed in the alternating current output circuit of the amplifier to 85 control the amplitude of the current supplied to the transformer 16 and therethrough to the load circuit.

90 In the arrangement shown in both of these figures, the operation of the system is the same. Normally an alternating current of frequency largely determined by the natural period of the tuned circuit 2 is supplied to the load circuit. Upon completion of the signal circuit 13, the supply of 95 alternating current is cut off so that silent and active intervals follow one another in any desired order determined by the opening and closing of the signaling circuit; hence, signals or spaces may be represented by either silent or impulse receiving intervals in accordance with the code decided upon.

100 In an arrangement which did not include the resistance 12, the completion of the signal path 13 caused a lowering of the impedance of the output circuit of the oscillator, since the portion of the inductance 3 in the input circuit of the tube 1 was thereby shunted through a portion of the resistance 9, in Figure 1 or short-circuited in 105 Figure 2. When this occurred, the tuning of the oscillatory circuit was subjected to variations due to the above mentioned change in the impedance across a portion of the inductance 3 and surges occurred both upon the opening and closing of the signal path. Resistance 12, by eliminating surges, sharpened the signal periods.

110 Since the form of carrier current supply 115 is immaterial from an operative viewpoint 120

it will be apparent that any other type of oscillator or source of supply may be utilized. Again complete wire circuits may be used in the arrangement shown in Fig. 1 and ground connections will be equally effective in the design shown in Fig. 2. The circuit changes necessary in either case being evident it is believed to be unnecessary to describe them further.

10 While the particular form of devices utilized and circuit connections employed have been described in order to clearly and completely set forth the invention, it is to be understood that this invention is not limited to these specific features but only by the scope of the appended claims.

What is claimed is:

1. A signal system comprising a source for continuously generating a current of carrier frequency, said source including a tuned frequency determining circuit, a work circuit connected thereto including an amplifier, means to shunt the carrier current from said amplifier in accordance with signals and means to maintain substantially constant impedance conditions in said work circuit irrespective of the operation of said shunting means.

2. A signal system comprising a source for continuously generating a current of carrier frequency, said source including a tuned frequency determining circuit, a work circuit connected thereto including an amplifier, means to divert the carrier current from said amplifier in accordance with signals and means to maintain substantially constant impedance conditions in said work circuit irrespective of the operation of said diverting means.

3. A signal system comprising a source for continuously generating a current of carrier frequency, said source including a tuned frequency determining circuit, an amplifier connected thereto, means to interrupt the flow of carrier current to said amplifier in accordance with signals and means to prevent changes in impedances external to said source from reacting upon said frequency determining circuit.

4. A signal system comprising a vacuum tube oscillation generator, a load circuit connected thereto including an amplifier, a controlled shunt path for the oscillations supplied by said generator, and reaction suppressing means included in said load circuit between said generator and the path.

5. A signal system comprising a vacuum tube oscillation generator, a load circuit connected thereto including a resistance and an amplifier, a controlled shunt circuit connected to said load circuit adjacent to said amplifier, and means to control said shunt circuit.

6. A signal system comprising a vacuum

tube oscillation generator, a load circuit connected thereto including a resistance and an amplifier, a controlled shunt circuit connected to said load circuit between the resistance and amplifier, and means to control said shunt circuit.

7. A signal system comprising a source of carrier current, a load circuit connected thereto including an impedance and an amplifier, a ground circuit connected to said load circuit between the impedance and amplifier, and means to control the ground circuit.

8. A signal system comprising a source of carrier current, a circuit connected to said source including reaction suppressing means and an amplifier, and means to ground the terminal of the reaction suppressing means which is adjacent to the amplifier.

9. A signal system comprising a vacuum tube oscillation generator, a circuit connected thereto including reaction suppressing means and an amplifier, and means to ground the terminal of the reaction suppressing means which is adjacent to the amplifier.

10. A signal system comprising a vacuum tube oscillation generator, a circuit connected thereto including a resistance and an amplifier, and means to ground the terminal of the resistance which is adjacent to the amplifier.

11. The combination of a generator for continuously producing a current of carrier frequency, said generator including a tuned frequency determining circuit, a transmission circuit to which oscillations are to be supplied by said generator, means for shunting said transmission circuit to control the application of oscillations thereto in accordance with signals, and means connecting said generator to said transmission circuit transferring oscillations therebetween which substantially prevents any change in the impedance of said transmission circuit attendant upon signaling from affecting the character of the oscillations produced by said generator.

12. The combination of a generator for continuously producing a current of carrier frequency, said generator including a tuned frequency determining circuit, a transmission circuit to which oscillations are to be supplied by said generator, means for shunting said transmission circuit to control the application of oscillations thereto in accordance with signals, a one-way conducting circuit connecting said generator to said transmission circuit transferring oscillations therebetween which substantially prevents any change in the impedance of said transmission circuit attendant upon signaling from affecting the character of the oscillations produced by said generator.

- 4
13. The combination of a generator for continuously producing a current of carrier frequency, said generator including a tuned frequency determining circuit, a transmission circuit to which oscillations are to be supplied by said generator, means for shunting said transmission circuit to control the application of oscillations thereto in accordance with signals, a circuit including a series resistance, connecting said generator to said transmission circuit transferring oscillations therebetween, said resistance having such magnitude as to substantially prevent any change in the impedance of said transmission circuit attendant upon signaling from affecting the character of the oscillations produced by said generator.
14. The combination of a generator for continuously producing a current of carrier frequency, said generator including a tuned frequency determining circuit, a transmission circuit to which oscillations are to be supplied by said generator, means for shunting said transmission circuit to control the application of oscillations thereto in accordance with signals, and means connecting said generator to said transmission circuit transferring oscillations therebetween which substantially prevents any change in the impedance of said transmission circuit attendant upon signaling from changing the frequency of the oscillations produced by said generator.
15. A generator for continuously producing a current of carrier frequency, an impedance to which said generator supplies
- current, a load circuit, means for shunting said load circuit in accordance with signals and a circuit including a series resistance connecting said load circuit to said impedance element, said resistance having such magnitude as to effectively prevent any tendency to short-circuit said impedance element. 40
16. The combination of an oscillator, for continuously producing oscillations, which includes a tuned frequency determining circuit and an oscillating current output branch, a transmission circuit, means for connecting said output branch to said transmission circuit, and a fixed resistance adapted to substantially prevent changes in the impedance of the circuit external to said output branch from affecting the character of the oscillations produced by said oscillator. 45
17. The combination of an oscillator, for continuously producing oscillations, which includes a tuned frequency determining circuit and an oscillating current output branch, a transmission circuit, and means for connecting said output branch to said transmission circuit including a fixed resistance adapted to substantially prevent changes in the impedance of the circuit external to said output branch from affecting the character of the oscillations produced by said oscillator. 50
